UNITED STATES PATENT OFFICE.

HOMER L. BOYLE, OF LANSING, MICHIGAN, ASSIGNOR OF ONE-HALF TO SAMUEL H. DAVIS, OF LANSING, MICHIGAN.

VACUUM-CLEANER.

1,208,735.

Specification of Letters Patent. Patented Dec. 19, 1916.

Application filed November 26, 1915. Serial No. 63,540.

To all whom it may concern:

Be it known that I, HOMER L. BOYLE, a citizen of the United States, residing at Lansing, in the county of Ingham and State of Michigan, have invented certain new and useful Improvements in Vacuum-Cleaners, of which the following is a specification.

This invention relates to vacuum cleaners for removing by suction particles of dust and other substances from carpets, rugs and the like, and the object of this invention is the construction of specially fashioned and arranged parts forming a cleaner that is light in weight, cheap to manufacture and easy to operate.

It is likewise an object of this invention to produce a cleaner of the nature set forth in which the dust-collecting receptacle is in immediate connection with the nozzle, and the air-suction devices are located in the rear of the casing. By reason of such special arrangement, the dust and foreign particles are strained from the air before it reaches the suction devices, which act only upon relatively clean air and do not readily become clogged with dirt.

It is also an object of this invention to provide a casing having in its front portion an air-tight compartment within which is located a dust strainer and collector having particular construction. The dust receptacle is removable, and means are further introduced including spring members whereby the dust receptacle is held yieldingly within the air-tight compartment, and, at the same time the front of the receptacle is pressed into contact with the opening in the nozzle, in order that the matter sucked up by the nozzle may pass directly into the receptacle or strainer.

The special construction and arrangement of the parts comprising this invention are illustrated in the accompanying drawings, of which—

Figure 1 represents a vertical, longitudinal section of all the parts assembled. The section shown in Fig. 1 is taken upon the indirect broken line $x-x$ of Fig. 2, which figure is a top plan view of this invention with the forward and hinged portion of the top of the casing removed to disclose parts beneath. Fig. 3 is a top plan view of a modification of the dust receptacle, and Fig. 4 is a cross section of such modification upon the broken line $y-y$ of Fig. 3. Fig. 5 is

a top plan view of a modified form of this invention with a portion of the forward part of the top of the casing broken away to exhibit the dust receptacle which is also of modified form and consists of a drawer 60 which may be drawn out from the side of the casing.

In all the views and throughout the description the same letter is used to designate the same part.

Considering Figs. 1 and 2, the casing A is provided with a pivoted bail B and operating handle b of usual form.

At the front of the casing is arranged the nozzle C, and it is advantageous though not essential to provide the little knob or lip a on the front of the nozzle, upon which the finger may be pressed to hold the casing down when it is desired to raise the forward and hinged portion D of the top against 70 any possible remaining partial vacuum below the top, or if it should stick. The hinges upon the top are marked d .

Interiorly the casing is divided into two compartments, and the front compartment 80 is closed at the bottom by the board e. The hinged top D covers the front compartment, and it is customary to provide the top D with a sheet of compressible packing F on its under side. The nozzle as shown opens 85 into or toward the front compartment, and the opening is framed by a sheet of packing f having an opening coinciding with the opening in the nozzle. The transverse partition which divides the casing into compartments is referred to by the letter E.

Within the air-tight front compartment is located the dust receiving and straining receptacle G. It has a front opening g arranged to register with the opening of the 90 nozzle, and the bottom H of the receptacle consists of gauze or other material suitable for the purpose of filtering the dust from the air. It will be noted in Fig. 1 that the bottom H inclines rearwardly and upwardly, 100 thus leaving a space below the bottom H and above the board e for the air to pass toward the rear compartment of the casing. The receptacle has the side wall opening h, covered by the air-straining material J, and the receptacle has also the rear opening K covered by the straining material j. The partition E has an opening k through which air may be drawn into the bellows L, of which there may be any number. By means 110

of the connection *l*, the bellows is operated by the driving wheel *M* in the ordinary manner, and it is advantageous to support the back board of the bellows by means of 5 the suspended and pivotally supported links *m*. The links prevent the movable ends of the bellows from dropping down upon the carpet during the operation.

In Figs. 1 and 2 there will be observed the 10 rollers *n* attached to the inside of the front of the receptacle, and the spring members *N* attached to the hinged top *d*, are so arranged as to engage and press upon the rollers. That engagement takes place when 15 the top is closed down to cover the front compartment, and the effect is to hold the receptacle *G* yieldingly in place within the compartment, and at the same time to press the front of the receptacle firmly against the 20 packing *g* in order that there will be no leak, and the full effort of the suction will be exerted through the opening *g* and through the nozzle *C*. Thus the nozzle and the dust receptacle are in operation immediately connected together. In Fig. 1 it 25 will be noted that the opening *k* in the transverse partition *E* is located near the bottom board *e* of the air-tight compartment, while the opening *g* through which the in-coming 30 air and dust enter the receptacle *G* is at a higher level. The dust-laden air is, therefore, sucked inwardly and downwardly and all of the air taken in passes through the strainer bottom and side openings of the 35 receptacle.

Figs. 3 and 4 illustrate a modified form of the dust receptacle. The modified receptacle *O* has the upwardly and rearwardly inclined bottom *P* composed of straining 40 material as already explained. The receptacle *O* also has the front opening *p* through which the dust-laden air enters, and the rear and side openings *Q* and *R*. Near the front the modified receptacle has the cross-bar *S*, 45 and a portion of the top of the receptacle is covered with the strainer material *s*, that extends also over the rear opening *Q*. The side opening *R* is covered with like strainer material *r*. The front of the modified receptacle is provided with the rollers *q* for engagement with the spring fingers *N* carried by the hinged portion of the top and already described.

The modified form of the invention shown 55 in Fig. 5 comprises the casing *T* that has the front end closed by the nozzle *t* in the same manner as before, and the casing is divided by the partition *U*. The opening of the nozzle toward the compartment 60 formed is framed by the sheet of packing *u*.

The dust receptacle *V* has substantially the same general construction as that described for the receptacle *G*, but, it is constructed in the form of a drawer having 65 the front board *W* and knob *w* by which

it may be drawn out from the side of the casing. It is advantageous to cover the inside of the board *W*, or at least the edge portions thereof with suitable packing *Z* in order that a tight joint may be made with 70 the side of the casing. In order that the drawer *V* may be held yieldingly in the front compartment of the casing *T*, and to keep the front of the receptacle always firmly pressed against the packing that 75 frames the nozzle, the vertical lugs *1* are provided on the back of the receptacle. The lugs have inclined sides, and when the drawer receptacle *V* is withdrawn or replaced in the compartment, the spring fingers *2* ride over the lugs and engage the inclined sides of the lugs, at the same time the springs press the receptacle against the packing *u*.

In the operation of this invention, 80 whether of the preferred form or of the modified form, the air and dirt enters the dust receptacle directly and the dust is deposited therein, while the relatively clean air passes off by way of the bellows located 85 in the rear part of the casing. If the dust to be collected is of a very light character, the modified form *O* of the receptacle which has the strainer material extended over a portion of the top is useful to baffle and 90 bring to rest eddies or whirls within the receptacle. In either form of the invention the dust receptacle or collector is easily and conveniently removed and replaced, without 95 raising the whole apparatus from the 100 ground.

Having now described this invention and explained the mode of its operation, what I claim is:

1. In a vacuum cleaner, the combination 10 with a casing having an air-tight compartment, of air-suction devices in communication with the said air-tight compartment, means for operating the said air-suction devices, a nozzle having an opening, the said air-tight compartment having an opening 11 registering with the opening of the nozzle, a removable dust receptacle having an opening registering with the said opening in the said compartment, the said receptacle having a portion provided with air-filtering material within the said air-tight compartment, the said air-tight compartment having an opening for the removal of the said dust 12 receptacle, means for closing the said opening when the said receptacle is in the said compartment, and devices arranged to exert force upon the said receptacle and the said closing means at the same time whereby said opening of said receptacle is held to the 13 opening of said compartment registering with the opening of the nozzle and the said compartment closing means are held closed.

2. In a vacuum cleaner, the combination 14 with a casing having an air-tight compart-

- ment, of air-suction devices in communication with the said air-tight compartment, means for operating the said air-suction devices, a nozzle having an opening, the said 5 air-tight compartment having an opening registering with the said opening of the nozzle, a rigid removable dust receptacle having an opening registering with the said opening in the said compartment, the said 10 receptacle having a portion provided with air-filtering material within the said air-tight compartment, the said compartment having an opening for the removal of the said receptacle, means for closing the said 15 opening when the said receptacle is in the said compartment, and spring devices arranged to exert force upon the said receptacle and the said closing means at the same time whereby the said rigid receptacle is 20 pressed bodily toward the nozzle and the opening of said receptacle is held to the opening of the compartment registering with the said opening of the nozzle and the said closing means are held closed.
- 25 3. In a vacuum cleaner, the combination with a casing having an air-tight compartment, a movable top covering the compartment, air-suction devices in communication with the said compartment, means for operating the air-suction devices, a nozzle opening into the said compartment, a removable dust receptacle having a front wall provided with an opening registering with the said opening to the nozzle, the said 30 receptacle having its top open near the said 35
- front wall, and means including springs attached to said movable top of said compartment and devices carried on the inside of said front wall of the receptacle and constructed to engage the said springs whereby the front 40 of the receptacle is held against the front of said compartment and the said top is at the same time held closed.
4. In a vacuum cleaner, the combination with a casing, of a driving wheel in the rear 45 of the casing, an air-tight compartment formed in the front of the casing, the said casing having a hinged top portion removably covering the said compartment, air-suction means arranged in the rear of the 50 casing and in communication with the said compartment, the said air-suction means being connected with and operated by the said driving wheel, a nozzle arranged at the front of the casing and opening into the 55 said compartment, a removable dust receptacle located in the said compartment and having a front opening arranged to register with the said opening in the nozzle, and means including spring members attached to the said hinged top of the casing and arranged to act against the front of the said receptacle to hold the said receptacle 60 yieldingly in the said compartment and at the same time to hold the said front opening of the receptacle in conjunction with the said opening of the nozzle.
- 65 In testimony whereof I affix my signature.

HOMER L. BOYLE.
